UNITED STATES PATENT OFFICE.

ARTHUR E. FOLSON, OF WINCHESTER, MASSACHUSETTS, ASSIGNOR TO WILLIAM M. WHITNEY, OF WINCHESTER, MASSACHUSETTS.

PLANING-MACHINE.

1,333,710.

Specification of Letters Patent. Patented Mar. 16, 1920.

Application filed August 8, 1919. Serial No. 316,230.

To all whom it may concern:

Be it known that I, ARTHUR E. FOLSON, a citizen of the United States, residing at Winchendon, in the county of Worcester and State of Massachusetts, have invented an Improvement in Planing-Machines, of which the following description, in connection with the accompanying drawings, is a specification, like characters on the drawings representing like parts.

The invention to be hereinafter described, relates to wood planing machines, and is an improvement upon the machine shown, described and claimed in my copending application, Serial No. 148,860, filed February 15, 1917.

The machine of said application comprises a frame having a rotary cutter mounted thereon and feed rolls for feeding the work past the cutter. To hold the work in proper engagement with the rotary cutter, there is provided a bridge member and a work engaging member relatively movable transversely of the machine frame having provision for causing the work engaging member to move to or from the work in the course of such relative movement. An adjusting screw is provided for producing the relative movement of the bridge and work engaging member, devices are provided for taking up lost motion between the bridge and work engaging member, and devices are provided for clamping the bridge and work engaging member together to secure the same in different positions of adjustment.

The aforesaid construction constitutes a good, efficient form of means for the purpose, but said construction is susceptible of certain improvements.

One of the objects of the present invention is to provide a bridge member and a work engaging member which will be simpler and stronger in construction, and better able to stand up under the heavy duty of holding the work in the proper relation to the rotary cutter.

Another purpose of the invention is to provide simpler and more efficient means for effecting the relative adjustment of the bridge member and work engaging member, and simple and efficient means which shall be readily accessible and easily operated for the purpose of clamping the bridge member and work engaging member together in different positions of relative adjustment.

In the use of the machine it is frequently desirable to obtain a slight variation in the pressure of the work engaging member against the work, and therefore, it is desirable to be able to obtain a nicety of relative adjustment of the bridge member and work engaging member. Another purpose of the invention, therefore, is to provide an index and scale which will readily enable a slight relative adjustment of said parts from a previous adjustment, and which will indicate the direction of adjustment necessary to move a work engaging member toward or from the work.

With the aforesaid and other objects in view, the character of the invention will be best understood by reference to the following description of one good form thereof shown in the accompanying drawings, wherein:

Figure 1 is a vertical longitudinal section through a wood planing machine embodying the invention;

Fig. 2 is a perspective view of the bridge member and work engaging member;

Fig. 3 on an enlarged scale is a detail view showing the index and scale for indicating the relative adjustment of the bridge member and work engaging member;

Fig. 4 is a plan of the work engaging member;

Fig. 5 is an end elevation of the work engaging member; and

Fig. 6 on an enlarged scale is a vertical section taken on line 6—6 of Fig. 2.

Referring to the drawings, the wood planing machine shown therein may have any suitable frame or support for the operating parts of the machine. In the present instance of the invention, a pair of side frames, such, for example, as the side frame 1 are provided, and are held in proper spaced relation by suitable transverse members. To support the work, a table 3 is provided extending between and mounted on the side frames.

To feed the work along the table, a pair of upper and lower in-feed rolls 5 are provided. The lower roll has a shaft 7 journaled in boxes 9 mounted on the side frames of the machine beneath the table, and the upper feed roll has a shaft 11 journaled in boxes adjustable vertically in guides in the side frames of the machine, said boxes being pressed downward by coil springs 13 confined between the upper ends of said boxes

and yokes 15. A pair of upper and lower out-feed rolls 17 are provided, the lower roll having a shaft 19 journaled in bearings in boxes 21 mounted in side plates of a carriage 22 to be referred to. The upper out-feed roll 17 has a shaft 23 journaled in bearings in boxes 25 adjustably mounted in guides in the side frames, and pressed downward by coil springs 27 confined between the upper ends 10 of said boxes and yokes 29.

The in-feed and out-feed rolls may be provided with suitable driving means well known in the art, and therefore, it is unnecessary to show and describe the same 15 herein.

A rotary cutter 31 is mounted on a shaft 33 journaled in bearings on the carriage 22 referred to. This carriage may be raised or lowered to raise and lower the cutter and 20 the lower out-feed roll 17 to vary the depth of the cut in the work as desired. The elevation of the carriage may be regulated by wedges 35 beneath the carriage and adjusted by devices 37. Since these wedges and 25 adjusting devices are well known in the art, it is unnecessary further to show and describe the same herein.

Next will be described the means opposed to the cutter for holding the work in proper 30 engagement therewith while the work is fed past the cutter by the in and out-feed rolls. This means, in the present instance of the invention, comprises a bridge member 39 located between the in and out-feed rolls, 35 and having ends 41 adapted to be supported on the opposed side frames of the machine. It is desirable to adjust the bridge member with respect to the side frames for purposes of preliminary adjustment. To accomplish 40 this, in the present instance, a pair of adjusting screw bolts 43 are provided for each of the ends 41, and are threaded in tapped holes in said ends. The lower ends of these screw bolts may rest upon the upper edges 45 of the side frames of the machine, as will be noted in Fig. 1. By adjustment of said screw bolts, the bridge member may be raised and lowered as desired, and one end of the bridge member may be raised or 50 lowered more than the other according to conditions as required. To secure the bridge member in its different positions of adjustment, screws 45 may be provided having their lower end portions 55 threaded into tapped holes in the side frames, and smooth portions adapted to project upward through smooth holes in the ends 41 of the bridge member. The upper end portions of the screws 45 may be threaded 60 to receive securing nuts 47. After the bridge member has been adjusted with the elevation desired, the nuts 47 may be tightened against the upper face of the bridge member and press the adjusting bolts 65 against the upper edges of the side frames of

the machine. The construction is such that the bridge member may be securely held in different positions of adjustment. Beneath the bridge member is a work engaging member 49 having a work engaging under face 70 51 which may be transversely rounded somewhat to facilitate feed of the work past the same. At the opposite ends of the work engaging member are upstanding flanges 53 having inclined upper edges 55. Coöperating 75 with the upstanding flanges 53 are flanges 57 projecting downwardly on the bridge member. These downwardly extending flanges have lower inclined edges 59 opposed to and engaging the upper edges 55 80 of the upstanding flanges of the work engaging member. To prevent lateral relative movement between the bridge member and work engaging member, the former may have tongues 61 entering grooves 63 on the 85 latter. The construction is such that when the work engaging member is adjusted transversely of the machine with respect to the bridge member, it will be moved downwardly toward the work or upward from 90 the work depending on whether the work engaging member is adjusted toward the right or toward the left of Fig. 2.

Next will be described the means for adjusting the work engaging member relatively to the bridge member transversely of the machine frame. This means, in the present instance, comprises a post 65 rising from and rigidly secured to or integral with the work engaging member, said post having a 95 wide base and tapering upward toward the upper end thereof which enters a box 67 on and integral with or rigidly secured to the bridge member. The box is of sufficient length to allow the post to move toward 100 and from the ends thereof in effecting the adjustment of the work engaging member. At the opposite ends of the box 67 are lugs 69 having holes tapped to receive adjusting screws 71. The construction is such that 105 these screws may be adjusted to push the post along the box and impart the degree of adjustment desired to the work engaging member. The ends of the screws freely engage opposite edges of the post, and do not 110 interfere with up and down movement of the post with the work engaging member in the course of the adjustment of the latter transversely of the machine frame.

As stated, one of the purposes of the invention is to provide means for indicating the adjustments of the work engaging member. This means, in the present instance, comprises an index 73 projecting upward from a plate 75 secured by screws 77 to the upper end of the post. Coöperating with this index is a scale 79 comprising graduations marked on a plate 81 secured by screws 83 to a lug 85 on the top of the box 67. The index 73 projects upward through 120 125 130

an elongated aperture 87 in the top of the box in front of the scale 79. The construction is such that the index moves with the work engaging member along the scale, and by reference to the graduations of the scale the work engaging member may be adjusted with desirable nicety of adjustment. The scale plate may have arrows and the words "to raise" and "to lower" marked thereon to indicate the direction of adjustment of the work engaging member to cause the same to move up or down.

Next will be described the means for securing the work engaging member to the bridge member in different positions of relative adjustment, and preventing lost motion between said parts. This means, in the present instance, comprises a pair of securing posts 87 rising from the work engaging member adjacent each end thereof. These posts project through elongated apertures 89 surrounded by bosses 91 projecting upward from the bridge member, and the tops of said bosses have an inclination corresponding to the inclination of the engaging edges of the flanges of the bridge member and work engaging member. Projecting upward from the securing post 87 are screws 93 entered loosely through holes in bars 95 resting on the upper inclined edges of the bosses 91. The upper end portions of the screws 93 are threaded to receive nuts 97 adapted to be adjusted into tight engagement with the bars 95. Since the bars 95 can not turn, the nuts on being tightened into engagement therewith, will be prevented from working loose.

The construction is such that when it is desired to adjust the work engaging member relative to the bridge member, the nuts 97 are released and then the adjusting screws 71 are adjusted as described to move the work engaging member transversely of the machine and thereby obtain the elevation of the work engaging member desired. After the work engaging member has been thus adjusted, the nuts 97 may be tightened, thereby to draw the upstanding flanges of the work engaging member up into tight engagement with the downwardly projecting flanges of the bridge member. Thus, the work engaging member may be securely held to the bridge member, and if the inclined edges of the flanges of said members become worn, the nuts 97 will always insure engagement of the edges of said flanges without lost motion.

In use, the bridge member may be given a preliminary adjustment with respect to the side frames of the machine, in order preliminarily to position the work engaging member with respect to the work, and then the work engaging member may be adjusted as described to furnish the desired nicety of final adjustment to secure the necessary engagement of the work engaging member

with the work properly to hold the work to the cutter.

By my invention, simple and efficient means is provided for holding the work properly to the cutter. The adjustments of the work engaging member may be quickly and readily effected, and said member may be positively held in its different positions of adjustment.

It will be understood that the invention is not limited to the specific embodiment shown, but that various deviations may be made therefrom without departing from the spirit and scope of the appended claims.

What is claimed is:—

1. In a machine of the character described, the combination of a cutter, a bridge member and a work engaging member opposed to said cutter, said members being relatively adjustable transversely of the machine with provision for moving the work engaging member toward or from the work on such relative adjustment thereof, said bridge member having elongated slots therein, and posts rising from said work-engaging member toward said slots with means for clamping said bridge member and work engaging member together in different positions of adjustment.

2. In a machine of the character described, the combination of a cutter, a bridge member and a work engaging member opposed to said cutter, and having pairs of flanges with inclined meeting edges for moving the work engaging member toward or from the work on relative adjustment of said bridge member and work engaging member transversely of the machine, and means for securing said members in different positions of adjustment.

3. In a machine of the character described, the combination of a cutter, a bridge member and a work engaging member opposed to said cutter, interengaging elements between the bridge member and work engaging member acting to move the work engaging member toward or from the work when the two members are relatively moved transversely of the machine, an adjusting member fast on one of said members, and a pair of adjusting screws on the other member having ends for engagement with opposed sides of said adjusting member to effect the relative adjustment of the bridge member and work engaging member.

4. In a machine of the character described, the combination of a frame, a cutter mounted therein, and work positioning means opposed to said cutter comprising a supporting member and a work engaging member having inclined interengaging parts acting to move one of said members toward or from the work when the two members are relatively moved transversely of the machine, an adjusting member on one

of said members, adjusting screw means on the other member coöperating with said adjusting member to effect said relative adjustment, and means coöperating with said 5 adjusting member for indicating said relative adjustment.

5. In a machine of the character described, the combination of a frame, a rotary cutter mounted thereon, and work 10 positioning means comprising a supporting member and a work engaging member having flanges with inclined tongue and groove connections therebetween, means to adjust one of said members relatively to the other to 15 move the work engaging member toward or from the cutter, and means for clamping said tongue and groove connections together to take up lost motion between the supporting member and the work engaging member and 20 securely hold said members in different positions of relative adjustment.

6. In a machine of the character described, the combination of a frame, a rotary cutter mounted on said frame, and work 25 positioning means opposed to said cutter comprising a work supporting member mounted on said frame, a work engaging member between said supporting member and cutter, said members having inclined 30 interengaging parts for moving the work engaging member toward or from the cutter on adjustment of said work engaging member relatively to the supporting member transversely of the machine frame, a 35 post rising from the work engaging member up to the supporting member, adjusting screw means mounted on the supporting member and coöperating with said post for moving the work engaging member trans- 40 versely of said frame, and means to secure said work engaging member in different positions of adjustment.

7. In a machine of the character described, the combination of a frame, a rotary cutter mounted thereon, and work positioning means opposed to said rotary cutter comprising a bridge member extending transversely of said frame and connected thereto, a work engaging member beneath 45 said bridge member, said members having inclined parts for effecting movement of the 50

work engaging member toward or from the cutter on adjustment of the work engaging member transversely of said frame, said bridge member having elongated apertures 55 therein and bosses surrounding said apertures with inclined upper edges, posts projecting from said work engaging member up through the elongated openings in said bosses, elements resting on the upper edges 60 of said bosses, and bolts coöperating with said posts and elements to secure the work engaging member to the bridge member in different positions of adjustment.

8. In a machine of the character described, the combination of a frame, a rotary cutter mounted on said frame, and work positioning means opposed to said cutter comprising a supporting member mounted on said frame, a work engaging member carried by the supporting member, an 65 adjusting member projecting centrally from said work engaging member up to said supporting member, means accessible above said supporting member for moving said adjusting member to adjust the work engaging member relatively to the supporting member, and means to secure said work engaging member to said supporting member in 70 different positions of adjustment.

9. In a machine of the character described, the combination of a frame, a rotary cutter mounted thereon, and work positioning means opposed to said cutter comprising a supporting member, a work 75 engaging member carried by said supporting member, said members having interengaging parts for moving the work engaging member toward or from the cutter on relative adjustment of said members transversely of the frame, said supporting member having pairs of elongated openings adjacent opposite ends thereof, pairs of posts rising from said work engaging member 80 through said elongated openings, elements mounted over said elongated openings, and means coöperating with said elements or posts to secure the work engaging member in different positions of adjustment.

In testimony whereof, I have signed my name to this specification.

ARTHUR E. FOLSOM.
